UNITED STATES PATENT OFFICE.

JOHN K. MILLER, OF MARIETTA, PENNSYLVANIA, ASSIGNOR OF ONE-HALF
TO FRANK THOMPSON, OF SAME PLACE.

DESIGN FOR A FRYING-PAN.

SPECIFICATION forming part of Design No. 28,363, dated March 8, 1898.

Application filed January 4, 1898. Serial No. 665,585. Term of patent 14 years.

To all whom it may concern:

Be it known that I, JOHN K. MILLER, of Marietta, in the county of Lancaster and State of Pennsylvania, have invented and produced 5 a new and original Design for Frying-Pans and Similar Articles; and I do hereby declare the following to be a full, clear, and exact description of the invention, such as will enable others skilled in the art to which it pertains to 10 make and use it, reference being had to the accompanying drawings, which form part of this specification.

My invention relates to designs for frying-pans and similar articles, the design being 15 illustrated in the accompanying drawings, in which—

Figure 1 is a perspective view of the pan embodying my design. Fig. 2 is a longitudinal sectional view of the same.

The essential feature of my design, as shown 20 in the accompanying drawings, consists in a pan having the partition B, extending there-across in a line with the handle, and the pouring-lip D.

Having thus described my design, what I 25 claim, and desire to secure by Letters Patent, is—

The design for a frying-pan or similar article, substantially as herein shown and described. 30

In testimony whereof I affix my signature in presence of two witnesses.

JOHN K. MILLER.
